(57) **CLAIM**

The ornamental design for a bottle, as shown and described.

DESCRIPTION

FIG. 1 is a front, upper perspective view of the inventive bottle;

FIG. 2 is a front view of the bottle depicted in FIG. 1, where side views and the rear view are identical to that depicted in FIG. 2;

FIG. 3 is a top view of the bottle depicted in FIG. 1; and, FIG. 4 is a bottom view of the bottle depicted in FIG. 1. The broken lines shown in the figures are included for the purpose of illustrating elements of the bottle and form no part of the claimed design.
